AUTOMATIC CONTROLLER FOR FACTORS OF COMBUSTION

John Jansson, Stockholm, Sweden, assignor to AB. A. Ekstroms Maskinaffär, Stockholm, Sweden

Filed Dec. 18, 1958, Ser. No. 781,243

Claims priority, application Sweden Apr. 26, 1957

5 Claims. (Cl. 236—26)

This invention relates to controls means and especially to automatic control for the several factors of combustion for devices such as boilers or the like, and is a continuation-in-part of application Serial No. 654,192, filed April 22, 1957, now abandoned.

From experience it is known that the amount of air required for complete combustion of fuel is in excess of the theoretical amount of air and that, at high combustion rates, the excess of air required over the theoretical amount is less than it is at low combustion rates. Also the excess required will be different for different fuels.

It has further become the practice to use two different fuels in the boiler, in which case it may be desirable to use a preponderance of one fuel at standby or light loads, and as the load builds up to vary the proportion between the fuels and to use a preponderance of the other fuel at heavy loads.

It will be understood then that there may be several factors contributing to the combustion in a device such as a boiler that, as the load on the boiler varies, must each be also varied, one at a different rate than another.

It is desirable also that the engineer operating the boiler may know at any time the operating conditions of the boiler and to be able to control not only the conditions of supply of the several requirements for combustion at the particular conditions of steaming, but also to be able to set the device so that, as conditions of steaming change, the controls for each of the factors of combustion will be adjusted to satisfy the new conditions according to the desires of the engineer.

It is a primary object of the present invention to provide control means from which each factor of combustion, for instance of a boiler, may be controlled for any steaming condition so that, as the load varies, each factor will be automatically controlled to vary in the correct proportion with respect to the other factors so that the boiler will be operated according to the engineer's desires under all loads.

It is a further object of the invention to provide an automatic control in which the control of each factor for each load condition from standby to full load may be pre-set to vary as required under the changing conditions.

It is a further object of the invention to provide automatic control means having a graphical representation screen that informs the operator of the setting of the controls under the existing load and also informs the operator what the setting of the controls will be under any changed load conditions.

Other and further objects and advantages will appear from the following specification taken with the accompanying drawings, in which like characters of reference refer to similar parts in the several views, and in which:

Fig. 1 is a fragmentary perspective view illustrating the invention,

Fig. 2 is a diagrammatic representation of the invention using a fluid operating medium, and

Figs. 3, 4 and 5 are diagrammatic representations il-

2

lustrating the invention using electricity as the operating medium.

In Fig. 1 the device comprises a carriage 101 that is mounted to move easily along a guide bar 102, a servo-motor means 103, shown here as a movable piston in a stationary cylinder, connected to carriage 101 by means of piston rod 136.

In front of the carriage 101 and supported by the stationary structure of which guide bar 102 is a part are two vertical supports 146 and 147.

Mounted in supports 146 and 147 opposite carriage 101 are pairs of adjusting screws 113—114, 115—116, and 117—118 that, upon rotation, may be advanced toward or retracted from the carriage 101. Each pair of adjusting screws is arranged to support one end of a straight edge 110, 111 and 112, respectively, that extends in parallel planes normal to the plane of carriage 101. These straight edges act as cam means to operate control elements 104, 105, and 106, as will appear below.

On carriage 101 are three control elements 104, 105 and 106, each mounted with its axis in the plane of one of the straight edges or cam bars 110, 111 and 112. Each control element is provided with a feeler element shown as a rod 107, 108 and 109, respectively, that may

be spring pressed outwardly toward the straight edges and that bear respectively on cam means 110, 111 and 112. It will be understood, therefore, that as the carriage 101 moves along guide bar 102 the plunger rod 109, for instance, will slide along its straight edge or cam 112 and if the end of straight edge 112 is farther from carriage 101 as it moves along guide bar 102 than is the end supported by adjusting screw 117, then, as the carriage 101 moves from left to right the plunger 109 will be progressively pushed

35 into its control means 106 and, as carriage 101 moves from right to left, the plunger 109 will progressively emerge from its control means 106 under the influence of the spring. The straight edge 112 could be adjusted so that the end adjusted by screw 117 is closer to carriage 101 and the end adjusted by screw 118 is farther from carriage 101 according to the results desired.

Straight edges 110 and 111 are similarly adjustable and each influences its appropriate plunger 108 or 107, according to the angle of the straight edge with respect to the plane of travel of carriage 101 and, of course, by its proximity as a whole to the plane of travel of carriage 101.

In order to have available a graphical representation of the position of the straight edges with respect to the 50 plane of carriage 101, each adjusting screw 113, 114, 115, 116; 117 and 118 is provided with a small pinion 119, 120, 121, 122, 123 and 124. Each pinion associated with an adjusting screw meshes with a rack 125, 126, 127, 128; and 129, 130, so it will be seen that as

55 one end of any straight edge is moved toward the plane of carriage 101 by rotation of its adjusting screw the rack associated with that adjusting screw is moved upwardly or downwardly proportionately by rotation of the adjusting screw that rotates the pinion. The ends of each 60 pair of racks are connected together by a thread 131, 132 or 133 which may be elastic and secured to each of its associated racks, or may be non-elastic and secured to one end and the other end extending over a pulley and counterweighted. These elements may also be of stiff wire in which case they are pivoted at one end to one of the racks and the other end extends slidably through a loop on the associated rack as seen in Figs. 2 and 5.

The threads or wires 131, 132 and 133 appear at a 65 screen 135 which, of course, may be marked with suitable indicia to give specific significance to the location of the threads at the screen. The traces of the threads 131, 132 and 133 on the window 135 graphically describe the posi-

tion and slope of the straight edges 110, 111 and 112, respectively. In order to have a graphical representation of the instantaneous setting of each of the control elements 104, 105 and 106 under the influence of straight edges 110, 111 and 112 respectively, a wire 134 is mounted to move with the control elements as they are moved along guide bar 102 and to provide a visible line or indicia at screen 135 which, as is clear in Fig. 1, intersects the traces of threads 131, 132 and 133. These intersections graphically illustrate the degree to which the plunger rods 107, 108 and 109 have each been pushed into its control means 104, 105 or 106 by its movement along its corresponding straight edge. Cylinder 103 is a means which, through piston rod 136, moves carriage 101 back and forth along guide bar 102.

If control element 106, for instance, controls fuel to a burner, it is at once apparent that as the carriage 101 moves along guide bar 102 the plunger rod 109 bearing against straight edge 112 is inserted further and further into control element 106 as the carriage moves toward the right and will emerge more and more as the carriage moves to the left. It will be seen, therefore, that if thrusting plunger rod 109 into control element 106 increases the flow of fuel and emergence of plunger rod 109 from control element 106 reduces the flow of fuel to the burner, then, by watching the movement of the trace of wire 134 as it crosses the trace of thread 133, the operator will be advised as to the instantaneous flow of fuel to the burner and will be advised as to the variations of such flow as they occur. The operator will, because there is a graphical representation of the condition or position of each of the control elements 104, 105 and 106, be able to visualize the conditions as they exist momentarily, and how they will each be changed with relation to each other as boiler conditions vary.

The position of the carriage 101 on the guide bar 102 may depend on the boiler pressure, as will be seen below. The graduations on the glass plate 135 parallel with the racks mark the boiler load or pressure that is indicated by the wire 134 carried by carriage 101, while the graduation of the glass plate at right angles to the racks marks the feeding of the various sources such as air, fuel, etc. indicated by the threads 131, 132 and 133.

When the adjustment screws 113, 114, 115, 116, 117 and 118 are screwed out as much as possible, the straight edges 110, 111 and 112 will be parallel in relation to the guide bar 102, and the tension in the springs of the control elements will correspond to the lowest outgoing control pressure, whereby the threads 131, 132 and 133 uniting the three pairs of racks will be located opposite each other and also opposite the graduation line lowest on the glass plate 135 and at right angles to the racks. When, on the other hand, the adjustment screws are entirely screwed in, the straight edges 110, 111 and 112 will still be located parallel in relation to the guide bar 102, but the threads 131, 132 and 133 will be located opposite the graduation line highest on the glass plate 135 and at right angles to the racks, and the tension in the springs of the control elements will correspond to the highest outgoing control pressure. Thus, the trace of the threads on window 135 is a direct indication of the outgoing control pressure. If the threads, due to the different degree of adjustment, are placed obliquely over the glass plate 135, the outgoing control pressure from the control elements will depend upon the position of straight edges 110, 111 and 112 and the momentary control pressures are indicated at that point where the wire 134 intersects the respective threads 131, 132, 133, since the position of the wire 134 is dependent on the adjustment of the servo-motor 103. Instead of reading as control pressures the graduations on window 135 are calibrated to read in appropriate units as, pounds per hour, for fuel, or c.f.m. for air, etc.

The specific control means 104, 105 and 106 is not of primary significance in the broad concept of the device.

It is only necessary that, as the plunger rods 107, 108 and 109 move into and out of control elements 104, 105 and 106, respectively, their position in the control element determines the flow of fuel, water, air, or whatever serves the particular plunger rod and control element is associated with. If the position determines the flow, then the position also indicates the flow.

In order to describe the working of a control system using the invention, reference is made to Fig. 2 which 10 shows a boiler 148, a pressure converter 149 and a diaphragm actuated valve 150. The pressure converter 149 is operated in this instance by means of pressure in the boiler.

The pressure converter 149 comprises a pressure sensitive diaphragm 151 which is connected to the boiler 148 by means of a conduit or pipe 159, a diaphragm 152 being acted upon by a control pressure medium from pipe 155, a rod 153 connecting said diaphragms (which are of different sizes so the pressure from 155 may be low), an outlet nozzle 154, a supply conduit or pipe 155 for the pressure medium, said conduit or pipe being provided with a reduction valve 156 and a throttling nozzle 157. The outgoing pressure from the pressure converter passes through a tube 158 leading to the servo-motor 103.

20 When there is a decreasing pressure in the boiler, the force acting upon the diaphragm 151 diminishes and is overcome by the force of the control pressure medium from pipe 155 acting upon the larger area of diaphragm 152. The rod 153 is lifted upwards, the pressure medium 25 below the diaphragm 152 then flows out through the nozzle 154 and a pressure reduction results in the conduit 158 and in the cylinder 103 which permits the spring 138 to press the piston 137, the rod 136, and the carriage 101 and control elements 104, 105 and 106 to the right to an extent corresponding to the pressure reduction in the cylinder 103. Since by adjustment of screws 117 and 30 118 the straight edge 112 is caused to assume an oblique position, the pressure rod 109 is pressed into control element 106 and compresses the spring 140 as the carriage 35 101 is moved to the right.

The diaphragm operated valve 150 to control, for instance, fuel to the boiler, comprises a valve box 159, a valve spindle 160, a diaphragm 161 and a spring 162. The valve 150 and the relay 106 of the device are 40 connected to each other by means of a conduit 144.

A pressure medium is fed to the control element 106 through the reduction valve 143 via the flexible conduit 142 and the throttle 145. Conduit 142 and pipe 155 may 45 receive pressure medium from the same source. While no pressure is developed in the relay when the outlet nozzle 141 is not obstructed by the diaphragm 139, a pressure equalizing the pressure of spring 140 is formed in the relay when, by means of plunger rod 109, the 50 spring 140 is pressed toward the outlet nozzle 141. 55 Thereafter the pressure resulting from the throttling of nozzle 141 is transmitted through the flexible conduit 144 to the valve 150 over diaphragm 161 which actuates the valve spindle 160 to open the valve to the extent determined by the balance between the pressure on diaphragm 60 161 and the strength of spring 162.

65 It is seen, therefore, that as pressure in the boiler drops the control element 106 is moved to the right so the pressure in conduit 144 increases in the manner described above and actuates the diaphragm motor valve 150 to increase the oil supply to the boiler in order to restore normal pressure conditions. In the case of increasing pressure in the boiler, the various moments of operation occur in a reverse manner. The working of 70 the control devices with regard to the other variables controlled by control elements 104 and 105 follows the same principles.

75 By setting the several straight edges or cams 110, 111 and 112, therefore, the control of each of the services to the boiler can be pre-set for every condition of operation. It will be noted, however, that in order to use the

device to automatically bring the boiler to a desired pressure and hold it there it is necessary to adjust the balance between the spring 138 and the pressure in conduit 158. A simple means to do this is by a means such as threaded element 138' which may be provided with indicia so that its position will state the pressure desired for boiler operation.

It is to be understood, however, that conditions other than boiler pressure may be used as the means to actuate a servo-motor 103. The differential pressure through a 10 metering orifice could be used so that the control elements would be moved in accordance with the volume of steam used so that upon sudden use of more steam the boiler fire would be increased without waiting for the boiler pressure to drop. Temperature also could be used, or several factors could be used to position the servo-motor 103.

The present application, however, is not concerned so much with the means to operate the servo-motor as with the control means shown in Fig. 1 that is operated by 20 any appropriate servo-motor device.

While the device described above is operated by compressed air or pressure oil it is, of course, also possible for the device to be operated by electrical impulses. Three embodiments for such operation are described 25 below.

Figure 3 shows an embodiment in which instead of the control element 106 a control element in the form of a solenoid 163 with a movable iron core 164 is used, which is kept pressed against the straight edge or cam 112 by means of a spring 165, the solenoid being fed from an alternating current source 166. A valve 169, corresponding to valve 150 in Fig. 2, is controlled by another solenoid 167 with an iron core 168 being kept in stretched position by means of a spring 170. Solenoid 167 is connected in series with the solenoid 163. When the carriage 101 is moved to the right, the iron core 164 is pushed into the solenoid 163 which causes the current passing through said solenoid to decrease, said decrease being due to the fact that the same current is also passing through the solenoid 167 and consequently the current also decreases in solenoid 167. The iron core 168 is therefore moved by means of the spring 170 and the valve 169 opens. The oblique position of the cam 112, which is determined by devices described above, can be read off as explained in connection with Fig. 1 with help of the traces of the adjustable threads on the plate.

Figure 4 shows an embodiment in which the movement of a valve 180 is actuated by a servo-motor 178, the shunt winding of which is connected as a Wheatstone bridge with two adjustable resistors 171 and 175. The resistor 171 is controlled by means of sliding contact 172 electrically insulated and connected to a rod 173 which, by means of spring 174, is kept pressed against the straight edge 112. The resistor 175 is controlled by sliding contact 176 moved by a rack 177 which cooperates with a toothed wheel 181 fastened to the axle of servo-motor 178. The spindle of the valve 180 is rigidly connected to the rack 177. This device, as stated above, operates on the principle of a Wheatstone bridge, i.e., when the carriage is moved in one or the other direction, moving contact 172 along resistor 171, a certain unbalance in voltage occurs between the resistors 171 and 175. A current is therefore passed through the shunt winding 179 of the motor 178 in one or the other direction, and the motor operates to restore the balance. The sliding contact 176 is moved so that a balance in voltage is obtained and the shunt winding 179 becomes dead.

A further embodiment using electrical resistors is shown in Figure 5. As it appears from the figures shown, the racks and indication plate are changed from the position in relation to the guide bar 102 that is shown in Fig. 1 and the aforementioned cams 110, 111 and 112, as well as all adjustable screws, are eliminated. The cam bars and plunger rods are replaced by contact rails 182, 183,

184, which are connected to the rods. Said rails cooperate with resistors 185, 186, 187 which are carried by carriage 101. These resistors 185, 186 and 187 are in the form of a wound rod and are arranged parallel to rods 190 and 191. The resistors are electrically insulated from the carriage and the contact rails 182, 183 and 184 are electrically insulated at 188 and 189 from the rods 190 and 191. The rods 190, 191 slide in the rails 192 and 193, said rails being fastened to the stationary guide bar 102. The adjustment of the valve 197, which may correspond to valve 150, is also here shown as a solenoid valve. Solenoid 194 with movable core 195 is kept in a drawn-out or valve closed position by the spring 196 and connected by arm 195 with the valve cone. During the 15 movement of the carriage to the right the portion of the resistor 185 being connected becomes smaller and smaller, and as the resistor is connected in series with the solenoid 194 the latter is activated by a current becoming stronger and stronger, so that the core 195 is drawn in deeper and deeper. During movement of the carriage to the left, the various operations occur in a reverse manner.

The electrical embodiments described above of course require electrical equipment designed in such a way that the position of the valve can be directly read off from the indication plate 135.

The control and indicating device described above showing three control elements can, of course, also be designed to include a greater number of control elements. Too large a number of such control elements in one and 30 the same device, however, will complicate the reading from the indication plate owing to the large number of threads required. In such a case it is possible to make a relay in such a manner that it gives an impulse to the servo-motor of a similar device or a similar device 35 may operate in parallel from the same impulse source.

Modifications within the scope of the claims are possible. Thus, the glass plate 135 may be replaced by a mirror, and the wire 134 may be replaced by a sheet moved forwards by the carriage 101 so that a part of 40 the illuminated window 135 is screened off.

While the device has been described in use as a control for a boiler, it will be apparent to those skilled in the control art that the device of the present invention may be used in many fields and that modifications can be 45 made without departing from the scope of the invention as defined in the appended claims.

What is claimed is:

1. In a device of the character described to control the supply of such factors as fuel and air necessary for 50 combustion in a boiler, a servo-motor arranged to respond to the instantaneous operating conditions of a boiler, a movable element guided for straight line movement under the influence of said servo-motor, the position of said movable element along said straight line 55 being determined by said servo-motor in response to said operating conditions, an observation window, first indicia means on said movable element forming a visible line on said window that moves parallel to itself as said movable element moves, at least one relay element including a rod slidably mounted at right angles to the direction of movement of said movable element mounted 60 on said movable element, said relay element being so constructed and arranged as to control the supply of one of said factors necessary for combustion by axial movement of said rod, adjustable cam means extending in the plane of movement of said rod generally in the direction of movement of said movable element, follower means 65 operating between said rod and said cam means so that said rod follows said cam means as said rod is moved therealong, means to adjust the angularity of said cam means with respect to the direction of movement of said movable means whereby said relay element may be adjusted in accordance with the adjustment of said cam means when said movable element moves under the influence of said servo-motor, and second indicia means

operated by said means to adjust said cam means, said second indicia means forming a visible line on said window indicative of the adjusted position of said cam means whereby the point of intersection of said lines formed by said first and said second indicia means will indicate the instantaneous value of the controlled supply of the factor necessary for combustion.

2. Means to simultaneously and automatically adjust a plurality of control devices in conformity with a preselected program comprising a slide element, means to move said slide element, a plurality of control devices mounted on said slide element, each of said control devices including an operating element movable in a direction normal to the direction of movement of said slide element to actuate said control devices, adjustable cam means for each said operating element lying parallel to the line of movement of said operating elements, adjustable means for each said cam means to alter and preset the position and angle of said cam means with respect to the line of movement of each said operating element, a window, means mounted on said slide element to form a first visible line on said window adapted to move parallel to itself as said slide element is moved, and means associated with each said adjustable means to produce a further visible line on said window representing the position and angle of each said cam means with respect to the line of motion of the associated control device whereby the intersection of said first visible line with said further visible line will indicate the instantaneous adjustment of each said control device and the several further visible lines will give a graph of the adjustments of said plurality of control devices as said slide element is moved under the influence of said means to move said slide element, said control devices each being operatively connected to a device to be controlled.

3. A device of the character described comprising a carriage, a guide bar, servo-motor means to move said carriage on said guide bar, at least one relay means rigidly mounted on said carriage, a pointer mounted on the carriage, a spring-actuated pressure rod extending from said relay so constructed and arranged that the position of said rod in the relay determines a signal coming from the relay, a straight edge, manually adjustable means comprising two adjustment screws extending towards and secured to said straight edge, follower means whereby said pressure rod slides along said straight edge when said carriage moves along said guide bar, a pair of racks located at right angles to and adjacent said adjustment screws, each said rack cooperating with the toothed wheel on one of said adjustment screws,

thread means connecting the ends of said pair of racks, and a glass plate forming a diagram window applied in a plane adjacent the said pointer and the said thread means, whereby by the position of the thread and of the pointer the adjustment of the relay can be read off, the said pointer being so positioned that it extends parallel with the racks.

4. A control device comprising a carriage mounted for linear movement along a path, a plurality of control elements mounted on said carriage, each said control element comprising a body housing adjustable control means, a feeler element mounted on said body and connected to said adjustable control means in such a manner that said control means is adjusted by the position of said feeler element with respect to said body, adjustable cam means for each said control elements lying generally parallel to the linear path of said carriage, each said cam means being associated with and in camming contact with the feeler element of one of said control elements, whereby as said carriage is moved along said path each of said control elements are adjusted in accordance with the adjusted position of its associated cam means, a screen, a plurality of movable indicia mounted to be normally visible on said screen, each said indicia being associated with one of said adjustable cam means and having a profile similar to the profile of the associated cam means, common means to adjust the position of each said cam means and its associated indicia means, whereby the position of said indicia means with respect to said screen is indicative of the position of its associated cam means with respect to its associated feeler element.

5. The device of claim 4, in which an indicia means is mounted on said carriage for movement therewith, said indicia means giving rise to a line visible on the said screen at right angles to the direction of movement of said carriage whereby the position of said line on said screen indicates the position of said carriage and the intersection of said line with the indicia of having a profile similar to the profile of one of said cam means will indicate the setting of the control means associated with said one of said cam means.
